UNITED STATES PATENT OFFICE.

JOHN A. PILCHER, OF ROANOKE, VIRGINIA.

CAR-TRUCK.

1,182,704.

Specification of Letters Patent.

Patented May 9, 1916.

Application filed March 10, 1915. Serial No. 13,373.

To all whom it may concern:

Be it known that I, JOHN A. PILCHER, a citizen of the United States, residing at Roanoke, in the county of Roanoke and State of Virginia, have invented certain new and useful Improvements in Car-Trucks, of which the following is a specification.

This invention relates to car trucks, and the principal object thereof is to provide an improved method of forming truck side frames of rolled sections.

Other objects are to provide an improved form of spacing members and of load-supporting members, and improved methods of securing the arch members to the truck oil boxes.

With these and other objects in view the invention consists in the formation, combination and arrangement of elements as will 20 be herein described and claimed.

In the drawings, Figure 1 is a side elevation of a portion of a truck embodying the present improvements. Fig. 2 is a partial plan view of the same and Fig. 3 is a transverse section of the same, taken on the line A B, Fig. 1. Fig. 4 is a perspective view showing the method of securing the ends of the side frame arch members together and to the oil boxes.

Referring to these drawings, wherein like parts are similarly designated, 1 represents an ordinary truck wheel mounted upon one end of an axle 2. It will be understood that a plurality of such axles with two wheels each occur, one only being shown for the reason that this form of truck construction is old and well known. At 3 is a customary oil box, which, with its contained parts forms a journal bearing for the axle 2, and this also is of standard M. C. B. construction.

The load of the car body is customarily carried on the center plate 4, which is usually a part of the bolster 5 and this bolster is supported on springs 6. The springs are carried on a seat 7, which is then supported on rollers 8. Various of the parts just enumerated are shown mainly in dotted lines for the reason that they have no essential bearing on the invention in question.

The truck side frame is composed primarily of a top arch bar or compression member 9, a bottom arch bar or tension member 10 and a spacing member 11. The said top and bottom arch members have

spaced, vertical relationship with each other at the central portion, and at the ends they converge and are co-actingly secured together so as to complete the triangle of members for truss action in the frame. The 60 spacing member 11 is detached so as to permit the arch members to be made of standard, rolled sections and is made of U-shape when viewed in side elevational view, the legs 12 and 13 thereof forming tie members between the top and bottom arch bars, or between the top arch bar and the bottom of the member 11, being secured to the top arch member by means of the rivets 14, and to the bottom arch member by means of the 65 rivets 15. The U-shape of this spacing member 11 provides a central opening 16, which serves to admit the springs and roller seat as well as the ends of the bolster 5, and the sides of the tie members 12 and 13 form 70 wearing faces 17 for co-operation with the adjacent sides of the bolster. The bottom portion 18 of the spacing member 11 is adapted to form seats for the rollers 8, thus serving as a load receiving means for the 75 load from these rollers which load is transmitted in turn through the bottom of this spacer casting to the arch member construction of the truck. It has been the general practice in trucks of this character to form 80 these tie members of vertically disposed bolts which are usually incased within column guides, the column guide serving as a guiding means for the bolster and the bolts serving as tie members for the bars. In such trucks the bottom arch bar is usually subjected to bending stresses from the bolster load for the reason that the load is applied to the bottom arch bars on flat surfaces or at 85 points removed from the tie members and out of the straight line of the tension in the bottom arch member. Also the column bolts 90 are called on to carry the full load from the bolster.

The present truck construction is constructed so as to cause the bottom arch member 10 to co-act with the bottom portion 18 of the spacing member 11 in such a manner as to avoid all bending loads in the bottom arch bar and at the same time relieve the tie members of a large portion of the load which they ordinarily carry. To perform this the central portion of the bottom arch member is made curved at 19 and from this curved portion are straight, upwardly in- 100 105 110

clined, tangential ends 20 which extend to and are co-actingly secured to the adjacent ends 21 of the top arch bar.

The bottom portion 18 of the spacing member 11, which serves as a load-receiving means, is made to conform to and bears upon the curved portion 19 of the bottom arch member and is supported entirely upon this curved portion of the bottom arch bar, hence no bending stresses will be imparted to the bottom arch member, for the load will be transmitted thereto in directions radial to the curved portion 19.

In order that the member 18 may be properly seated on the bottom arch bar, and in order further that the load will be imparted to the full length of the curved portion, leaving no unsupported portion of the member 10 out of line with the tension loads, this spacing member 11 extends slightly beyond the curve 19, being made with straight, tangential extensions 22 at the ends, which coincide with the tangential portions 20 of the bottom arch bar. Thus the bottom portion of the spacing member forms means for transferring the load to the bottom arch member as direct stresses, and furthermore the tie members 12 and 13 serve now only to take care of the upward reaction due to the angularity of the top arch bar at 23, hence the tie members act in reality between the load-supporting portion 18 and the top arch bar 9 only, the rivets 15 serving as restraining means only.

means only.

35 In order to restrain the oil boxes from longitudinal movement and at the same time to take up any load due to bending of the arch bars over the oil boxes, the tie members 25 are supplied, extending from the oil boxes to the truss proper. The oil box thus forms in some instances a part of the truss structure. The tie members 25 also serve to restrain the oil boxes when the brakes are applied to the wheels. At 24 I have shown means for attaching this box tie bar 25 to the spacing member 11, thus providing means through this spacing member for securing the bottom of the oil boxes to the truss member 10 without weakening this bottom arch member by cutting unnecessary holes in the same, it frequently happening that the rivets 15 are not in a correct location to serve as securing means for the bars 25.

40

45

50

55 It has furthermore been customary in arch
bar trucks to bring the top and bottom arch
bars together over the oil boxes and co-
-actingly secure these members together by
means of the box bolts 26. This form of
60 construction necessitates the intersection of
the truss lines at a point near the inner edge
of the oil box, with a consequent bending
moment in the horizontal portions of the
arch members over the oil boxes. I have
65 now provided an improved method of join-

ing these arch members together over the oil boxes, and also of securing the oil boxes thereto. To accomplish this the oil box 3 is secured to the end of the top arch member only by means of the bolts 26. The bottom arch member is made bifurcated at the ends and the resulting legs 27 have spaced relation with each other transversely of the truck. These legs 27 terminate in enlargements 28 through which are the pierced holes 29, the same being disposed transversely of the truck. The holes 29 register with a similar hole in a similar enlargement 30 on the top arch member, and the pin 31 passes through and thus co-actingly secures together these arch members. The loads are thus equalized in the truss structure without passing through the box bolts as a shearing load, and furthermore, the intersection of the truss lines is carried ahead to a point well over the oil boxes so that practically no bending occurs in the portion of the arch members over the oil boxes. The enlargements 28 may have bearing on the top of the oil box if desired to somewhat relieve the pin 31. The end of the top arch member being disposed between the legs 27 of the bottom arch member, the pin 31 is placed in double shear and the reactions from the truss are centrally equalized. Furthermore, the central disposition of the member to which the oil box is secured provides more simple means for disposing of the bolts 26 and puts the vertical load centrally on this oil box.

The spacing member 11 is shown as an integral casting, although it might be made otherwise. Also the customary hanger brackets 32 are shown as cast integral with these spacing members.

It will be seen that those skilled in the art might make alterations in the embodiment of my invention within the scope of the claims without departing from the spirit thereof.

Having thus described my invention, what I claim is:

1. In a car truck, a side frame comprising a top arch member, a bottom arch member in spaced vertical relationship therewith, and a central spacing member therebetween, the said bottom arch member embodying a central curved portion with straight, upwardly inclined, tangential ends, the said ends extending to and being co-actingly secured to the adjacent ends of the said top arch member and being bifurcated, and each of the legs thereof being provided with an enlargement, pierced transversely of said member, the ends of the said compression member being disposed between the legs of the bifurcated ends of the said bottom arch member and being provided with similar pierced enlargements adapted to register with those of the bifurcated ends of the bottom arch 130

- 16   member, and pins disposed through said
17   spaced enlargements and adapted to co-act-
18   ingly connect the said top and bottom arch
19   members.
- 20   2. In a car truck, a plurality of axles and
21   oil boxes, a trussed side frame supported at its
22   ends upon the oil boxes of adjacent axles,
23   said side frame comprising a top arch mem-
24   ber having vertically disposed holes at the
25   ends thereof suitable for the attachment
26   thereto of the said oil boxes, a bottom arch
27   member in spaced vertical relationship with
28   the said top arch member at the central portion
29   of said side frame and terminating at its
30   ends adjacent the ends of the said top arch
31   member, the ends of the said bottom arch
32   member being bifurcated and the resulting
33   legs having spaced relation with each other
34   transversely of the truck, the ends of the
35   said top arch member being embraced be-
36   tween the legs of the ends of the said bottom
37   arch member and being co-actingly secured
38   thereto.
- 39   3. In a car truck, a plurality of axles and
40   oil boxes, a trussed side frame supported at
41   its ends upon the oil boxes of adjacent axles,
42   said side frame comprising a top arch mem-
43   ber, a bottom arch member in spaced vertical
44   relationship with the said top arch mem-
45   ber at the central portion of said side frame
46   and terminating at its ends adjacent the
47   ends of the said top arch member, the ends
48   of the said bottom arch member being bifur-
49   cated and the resulting legs having spaced
50   relation with each other transversely of the
51   truck, the ends of the said top arch member
52   being embraced between the legs of the ends
53   of the said bottom arch member and being
54   co-actingly secured thereto, and means for
55   the attachment of oil boxes to the ends of the
56   said trussed side frame.
- 57   4. In a car truck, a plurality of axles and
58   oil boxes, a trussed side frame supported at
59   its ends upon the oil boxes of adjacent axles,
60   said side frame comprising a top arch mem-
61   ber, a bottom arch member in spaced vertical
62   relationship with the said top arch member
63   at the central portion of said side frame and
64   terminating at its ends adjacent the ends of
65   the said top arch member, the ends of the
66   said bottom arch member being bifurcated
67   and the resulting legs having spaced relation
68   with each other transversely of the
69   truck, the ends of the said top arch member
70   being embraced between the legs of the ends
71   of the said bottom arch member and being
72   co-actingly secured thereto, and means for
73   the attachment of oil boxes to the ends of the
74   said top arch member.
- 75   In testimony whereof I affix my signature
76   in presence of two witnesses.

JOHN A. PILCHER.
